ELECTRIC SWITCH

George B. Benander, Oaklawn, R. I., assignor to
Monowatt Electric Corporation, Bridgeport,
Conn., a corporation of Connecticut

Application May 18, 1939, Serial No. 274,367

10 Claims. (Cl. 200—67)

The present invention relates to electric switches, and it is an object of this invention to provide an improved switch construction which is durable in use and, at the same time, simple, easily assembled and economical to manufacture.

It is another object of this invention to provide a novel construction and arrangement for securing a cover and mounting strap to a switch casing.

Further objects and advantages of the present invention will become apparent as the following description proceeds, reference being had to the accompanying drawing, in which Fig. 1 is a plan view of an electric switch embodying the present invention; Fig. 2 is an elevational view in section of the switch of Fig. 1; and Fig. 3 is an exploded view in perspective showing the details of the switch construction.

In the embodiment of my invention illustrated in the drawing a body 10 is recessed from one face and provided with a cover 11 to form a housing for the switching mechanism. The housing is preferably molded from any suitable insulating material such as a phenolic condensation product. The opposite side walls of the recess are provided with aligned grooves 12 which open on the recessed face of the body and are shaped to provide bearing surfaces for pivotally mounting an operating lever 13 and a movable contact structure illustrated generally by the numeral 14. In the present construction the movable contact structure comprises a single sheet metal stamping of good conducting material having a pair of spaced parallel blades 15 formed with contact portions 16 at their opposite ends. The blades are connected together by a substantially U-shaped bridging portion 17. An integral trunnion 18 extends laterally from the central portion of each of the blades 15 and is positioned in the V-shaped bottom portion 19 of one of the grooves 12. The operating member 13 which may also be formed of molded insulating material extends through an opening 20 in the cover 11 and is provided with a pair of laterally extending cylindrical trunnions 21 which are received in suitable curved bearing surfaces 22 formed at the upper ends of the groove 12. The cover 11 is provided with suitable semi-circular bearing surfaces 23 adjacent the side walls of the opening 20 and in alignment with the upper ends of the grooves 12. The bearing surfaces 22 and 23 cooperate to mount the operating lever for oscillation about its trunnions when the cover is secured to the body. An over-center compression spring 24 is positioned

at one end on the central portion of the U-shaped bridging portion 17 of the movable contact structure by a circular flange 25 which is formed integral therewith. A flanged cylindrical sleeve 26 is fitted into the opposite end of the compression spring and forms a suitable bearing surface for a rounded portion 27 formed on the inner end of the operating lever 13.

A stationary contact and terminal structure is secured in the casing adjacent each end thereof. In the three-way switch illustrated in the drawing a stationary contact and terminal structure illustrated generally by the numeral 28 comprises a single sheet metal stamping having a flat elongated terminal strip 29 and an upper and lower pair of contacts 30 and 31, respectively, which extend substantially normal to the terminal strip and gives the stamping a generally U-shape. The terminal strip is provided with spaced threaded openings for the reception of suitable binding screws 32 for securing circuit wires to the terminal. The contact and terminal structure is positioned in the casing with the terminal strip lying against one of the end walls and with the contacts 30 and 31 extending inwardly in substantially parallel relation to the side walls of the casing. Integral ribs 33 are formed on the side walls near the end of the casing and engage the edge portions 34 of the terminal strip to hold it against the end of the casing. An integral wedge-shaped lug 35 extending from the lower end of the terminal strip is positioned in a similarly shaped recess 36 formed in the end of the bottom wall 37 of the body and prevents endwise movement of the contact structure relative to the body. An integral lug 38 extending from the opposite end of the terminal strip projects through an opening or notch 39 in the cover 11 and has its outer end bent over into engagement with the shoulder 40 to clamp the cover against the recessed face of the switch body. The shoulder 40 is preferably recessed from the upper surface of the cover 11, so that the end 45 of the lug will not interfere with mounting the switch against the rear face of a wall plate.

The other stationary contact and terminal structure is similar to that just described but is formed in two pieces which are mounted in insulated relation in the opposite end of the casing. The lower terminal 41 and contacts 42 are secured to the switch body in the same manner as that described in connection with the contact structure 28 by a wedge-shaped lug 35 and cooperating recess 36. The terminal 41, like

terminal strip 29, is provided with a threaded opening for the reception of a suitable binding screw 32 for attaching the bared end of an external circuit conductor to the stationary contact structure. Another terminal 43 with a pair of extending contacts 44, similar to the upper portion of the contact structure 28, is mounted above the terminal 41 and separated therefrom by a plate of insulating material 45 having edge extensions 46 which are positioned between the end wall of the casing and the ribs 33. In order to secure the terminal 43 and contacts 44 in the casing, a plate 47 is secured to the outer surface of the terminal strip by a binding screw 48. The plate is arranged to engage a shoulder formed on the end wall of the switch body by one of the openings 49 which are formed in the opposite ends of the switch body to provide access to the terminals for the purpose of making the necessary circuit connections therewith. The plate 47 is provided with an integral lug 50 which passes through an opening 51 in the terminal 43 and engages the inner surface thereof to prevent the plate from falling out should the binding screw 48 be removed. The terminal 43 is provided with a lug 38 which extends through a notch 39 in the cover and is bent over into engagement with a shoulder 40 in the same manner as the lug 38 of the terminal strip 29.

With the stationary contact and terminal structure described above, a three-way switch is provided. A single pole switch may be provided by making both stationary contact structures similar to that designated by numeral 28, but with one structure having the upper contacts 30 omitted and the other structure having the lower contacts 31 omitted.

With the construction thus far described it is apparent that oscillation of the operating lever 13 is effective to move the movable contact structure 14 from one position to another with a snap action through the action of the over-center spring 24. In case the contacts of the switch stick so that the pressure of the over-center spring is not sufficient to start the movement of the movable contact structure, a positive driving connection between the operating lever and the movable contact is provided. The operating lever is provided on its opposite faces with lugs 52 which are molded integrally therewith and lie on opposite sides of the axis of oscillation of the lever. The movable structure is provided with shoulders 53 which extend slightly above the trunnions 18 and lie in the path of the lugs 52 when the operating handle has been moved through its center position without moving the movable contact structure. As clearly indicated in the drawing, the shoulders 53 face in opposite directions so that a different one of the shoulders is engaged by one of the lugs 52 when the operating lever is moved in opposite directions.

In order to reduce arcing and increase the life of the contacts, a substantially U-shaped shield 54 of insulating material is provided for each of the stationary contact and terminal structures. As illustrated, the shield is formed of suitable sheet insulating material and positioned between the pairs of stationary contacts extending from the terminal plates 29, 41 and 43. The free edges of the U are normally spaced slightly farther apart than the distance between contacts so that the tendency of the shield to unfold holds the arm portions thereof in engagement with the inner surfaces of the stationary contacts and aids in positioning the shields with respect

to the switch casing. Integral ribs 55 formed on the bottom wall 37 of the switch body reinforce the same and aid in positioning the shields 54. In the extreme positions of the movable contact structure an edge of the bridging portion 17 thereof engages one of the shields which acts as a stop. The shield is more resilient than the molded body and as a result this arrangement provides a much quieter operating switch than those in which an integral stop lug is provided on the switch body.

The present invention also provides a novel arrangement for securing a mounting strap to the switch casing. A mounting strap 56 having a central aperture 57 of substantially the width of the switch body is provided with a plurality of inwardly extending integral lugs 58. The lower face of the cover 11 is provided with notches 59 extending inwardly from its opposite edges and spaced to receive the lugs of the mounting strap. The notches are preferably of the same depth as the thickness of the lugs 58 so as to provide a flush mounting. It is of course possible to form a portion of the notches 59 in a portion of the upper face of the switch body or to provide the notches entirely in the switch body. With this arrangement it is only necessary to position the mounting strap on the cover with the lugs 58 positioned in the notches 59 before assembling the cover on the switch body. When the cover is fastened to the body the mounting strap is tightly clamped therebetween and prevented from movement with respect to the switch body.

The construction described above requires few parts which are very easily assembled. It will be noted that no additional fastening means are required to mount the stationary contacts in the switch casing or to secure the cover to the switch body. The construction also simplifies the assembly of the switch and mounting strap.

What I claim as new and desire to secure by Letters Patent of the United States is:

1. In an electric switch, a casing recessed from one face, stationary contact structures positioned in said body adjacent the opposite ends thereof, at least one of said stationary contact structures including a conducting strip extending along an end wall of said casing and having a lug projecting from each end thereof, the lug extending from one end of said strip having engagement with said casing to secure said one contact structure against endwise movement relative to said casing, a lug projecting from the other stationary contact structure, a cover positioned on said casing and having an aperture at each end to receive the lugs projecting from the other end of the conducting strip of said one contact structure, and said lug projecting from the other contact structure, said last-mentioned lugs having portions thereof bent into engagement with an outer surface of said cover to hold it assembled on said casing.

2. In an electric switch, a body of insulating material recessed from one face, stationary contact structures positioned in said body adjacent the opposite ends thereof and secured against endwise movement, a mounting strap having an opening therein positioned on the recessed face of said body with at least a portion of the walls defining said opening extending over a portion of the recessed face of said body, a cover positioned on said body, integral lugs extending from one end of each of said contact structures and having engagement with an outer surface of said

cover to hold said cover and said mounting strap assembled on said body.

3. In an electric switch, a body recessed from one face, stationary contact structures positioned in said body adjacent the opposite ends thereof and secured against endwise movement, a mounting strap having an opening therein and a plurality of integral projections extending inwardly from the walls of said opening, a cover positioned on said body, the recessed face of said body and the lower face of said cover being shaped to provide openings for the reception of the inwardly extending projections of said mounting strap, and an integral lug extending from one end of each of said contact structures and engaging an upper surface of said cover to hold said cover and said mounting strap assembled on said body.

4. In an electric switch, a body of insulating material recessed from one face, a cover of insulating material positioned on the recessed face of said body and cooperating therewith to form a housing, a mounting strap having an aperture therein positioned on the recessed face of said body with a portion of the walls defining said aperture overlying the face of said body, said housing being recessed at the junction of said body and said cover to receive the overlying portion of said mounting strap, and means for securing said cover to said body and for clamping said mounting strap therebetween.

5. In an electric switch, a body recessed from one face, stationary contact and terminal structures positioned in said body adjacent the opposite ends thereof, each of said contact and terminal structures including a supporting strip extending along an end wall of said body and having contacts extending inwardly therefrom in spaced parallel relation, and a substantially U-shaped shield of insulating material positioned between said contacts and having the opposite arm portions thereof in frictional engagement with the inner surface of said contacts.

6. An electric switch comprising a casing, stationary contact and terminal structures positioned in said casing adjacent the opposite ends thereof, each of said contact and terminal structures including a conducting terminal strip extending along an end wall of said casing and having contacts extending inwardly therefrom in spaced relation, a substantially U-shaped shield of insulating material positioned between said contacts and a movable contact structure mounted for oscillation with respect to said casing and having a portion for engaging one of said shields in each of its extreme positions to limit the oscillating movement thereof.

7. In an electric switch, a body of insulating material recessed from one face and provided on opposite side walls with aligned slots, a movable contact structure having laterally extending trunnions positioned in said slots, an operating lever having laterally extending trunnions positioned in said slots above the trunnions of said movable contact structure, a compression spring interposed between the inner end of said operating lever and said movable contact structure, stationary contact structures positioned in said recess adjacent the opposite ends of said body and secured against endwise movement relative to said body, a cover for said body having an opening therein through which said operating

lever extends, and an integral lug projecting from one end of each of said stationary contact structures having a portion thereof bent into engagement with an outer surface of said cover to hold said cover on said body and the trunnions of said operating lever and said movable contact structure in said aligned slots.

8. An electric switch comprising a casing, stationary contact structures positioned in said casing adjacent the opposite ends thereof, each of said structures including a supporting strip extending along an end wall of said casing and having contacts extending inwardly therefrom in spaced relation, a movable contact structure of substantially U-shape mounted in said casing for oscillation with respect thereto and arranged to connect electrically certain of said stationary contacts in at least one of a plurality of operative positions, means for moving said movable contact structure from one position to another with a snap action, said movable contact structure including spaced contact arms resiliently engaging certain of said fixed contacts in the closed circuit positions of said movable contact structure, and a member of sheet insulating material of substantially U-shape positioned between said stationary contact structure and constructed and arranged to limit the oscillating movement of said movable contact structure and to diminish sparking between the contact portions of said fixed and movable contact structures as the contact portions thereof are separated.

9. An electric switch comprising a casing, stationary contacts secured in said casing adjacent the opposite ends thereof, a movable contact structure mounted for oscillation with respect to said casing and arranged to connect certain of said stationary contacts in at least one of a plurality of operative positions, means for moving said movable contacts from one operative position to another with a snap action, a member of sheet insulating material positioned in said casing adjacent each end thereof and so constructed and arranged with respect to said movable contact structure as to engage the same in each of its extreme positions to limit the oscillating movement thereof, said members of sheet insulating material also being so constructed and arranged with respect to the contact portions of said stationary contacts and said movable contact structure as to engage the contact portions of the latter during movement thereof from one circuit controlling position to another to cool said contact portions and diminish sparking.

10. In an electric switch, a substantially rectangular body recessed from one face thereof, stationary contact structures positioned in said body adjacent the opposite ends thereof, each of said stationary contact structures including a terminal strip extending along an end wall of said body and having integral contact members extending inwardly into the recessed portion of said body, each of said contact structures also having an integral lug projecting from the recessed face of said body, means for securing said contact structures in said body against relative endwise movement with respect thereto, and a cover positioned on said body, said lugs being bent into engagement with an outer surface of said cover to hold it assembled on said body.

GEORGE B. BENANDER.
